UNITED STATES PATENT OFFICE.

FREDERICK HEBERLEIN, OF CLEVELAND, OHIO.

KEYHOLE PLUG AND CLAMP.

Application filed August 11, 1927. Serial No. 212,231.

The present invention provides a device whereby the lock of a door is rendered thief-proof after it has once been locked. The advances made in the art of skeleton key making and other forms of devices used in picking locks have made it almost impossible to obtain a lock that cannot be picked and its effectiveness thereby destroyed.

This invention provides a simple device that is adapted to be applied to the keyhole on one side of a door, thereby preventing the unlocking of the door from the opposite side. When availed of, a keyhole plug made along the lines of my invention will cooperate with the lock in affording a locking combination, the effectiveness of which may be overcome only by a complete destruction thereof.

In attaining these ends a plug or closure is provided for the keyhole of the lock, with which the invention is intended to be used, together with certain instrumentalities that retain the plug in the hole as well as facilitate the application and removal of the plug.

This invention includes certain novel constructions embodied in the plug, whereby it is in no way subject to being removed or deformed after it has been placed in the keyhole. This is accomplished by forming the end of the plug that enters the hole in a "diamond point" and then case hardening it. Such a plug will be found to be impervious to any illicit operations which may be made thereon, aiming at its removal from the lock, to allow for the unfastening thereof.

A more particular object of this invention is to provide means for holding the plug in a keyhole, together with additional means that may be employed, as desired, in rendering the functioning of the first named means a positive fact. In carrying out this idea, a plate designed to afford a groove or trough, adapted to receive a portion of the plug, is provided. This plate is fastened to either the door or door-frame, as found suitable. It will be noted that when a portion of the plug is resting in the groove or trough, the keeper means, in the form of a U-shaped plate, is provided, which positively holds it therein.

With these and other objects in view, as will in part be hereinafter stated, and in part become apparent, the invention comprises certain novel constructions, combinations, and arrangements of parts as will be subsequently specified and claimed.

For a complete understanding of the invention reference may be had to the following descriptions and accompanying drawings in which:

Figure 1 is a front elevation showing my keyhole plug and clamp applied to a door, the illustration of the door and its frame being fragmentary and broken away.

Figure 2 is a cross sectional view taken on the line 2—2 of Figure 1, looking in the direction indicated by the arrows.

Figure 3 is a detailed perspective of the plug itself, showing more particularly the diamond point and angular formation thereof.

Figure 4 is a detailed perspective of the keeper.

Figure 5 is a view showing the plate attached to the door frame rather than the door.

Figure 6 is a front elevation showing a slight modification in which the keeper is notched for holding it in position when not in use.

While the preferred form of the invention is herein set forth it is to be understood that I am not to be limited to the exact construction illustrated and described, because various modifications of these details may be provided in putting the invention into practice within the purview of the appended claims.

A keyhole plug and clamp made in accordance with this invention is adapted to be applied to either side of a door making use of any of the well known locks having keyholes. No particular shape or size of the keyhole is pertinent so far as the application of this invention is concerned as the plug included in the device may be made in any size found desirable. A keyhole plug and clamp made along the lines of my invention comprise the following parts: a plug or closure member, a retaining plate, and keeper. In Figure 1 these parts are shown as they are applied to a door in the manner in which they are intended to be used.

In Figure 1 a door A and a door-frame B, in which it is mounted, are both shown in part, as a complete illustration thereof is not deemed necessary for an understanding of this invention. The door A has a keyhole 1 that receives a key when the lock is operated. This keyhole is surrounded by a key plate 2. All of the structure just described is a part of the construction ordinarily embodied in the lock of a door.

A plug or closure member 3 is provided that is designed to close or stop up the keyhole 1, thereby preventing the insertion of a key, which is necessary for the operation of the lock. It will be noted that this plug member is applied and removed from one side of the door so as to lock the door against opening from the opposite side. This plug member 3 comprises the plug portion 4, which 5 enters the keyhole when the device is in use, and the portion 6 bent to substantially a right angular relationship with the portion 4. The plug portion 4 has a diamond point 5 thereon, as clearly shown in Figure 3, and is case 10 hardened. The particular construction of this plug is a very important feature of this invention, as the case hardened diamond point makes it practically impossible for the plug to be deformed or removed while in the keyhole. Obviously the device would still 15 function if this diamond point construction were eliminated, but it is, however, the preferred form of my invention.

In order to prevent the removal of the 20 plug from the keyhole, a retaining plate 7 is provided. In this instance I have shown the plate applied to the door. It is to be understood, however, that it may also be applied to the door frame, as illustrated in Fig. 5. 25 When applied in this manner the portions 6 of the plug member 3 functions as a bolt in adding to the locking effectiveness of the lock. The plate 7 is formed so as to provide 30 a groove or trough 8 that is adapted to receive the portion 6 of the plug under certain 35 conditions, namely, when the plug is to be retained in the keyhole. It is notable that I have shown the plate 7 fastened to the door, 40 preferably by screw fastening means 9, although any equivalent thereof found suitable could just as well be employed. Projecting from the upper end of the plate 7 is a 45 screw 10 that is designed for a purpose to be hereinafter described.

After the door has been locked the portion 50 4 of the plug 3 is inserted in the keyhole, after which it is turned therein so that the portion 6 rests in the groove or trough 8. Attention 55 is called to the fact that any removal of the plug from the opposite side of the door is now prevented. To insure retention of the portion 6 in the trough a keeper member has been designed to positively hold the portion 6 of the plug therein.

A keeper 11, of substantially U-shaped 60 formation, is held in clamping position by a thumb or wing nut 13, which threads on the screw 10, projecting through a channel 12 formed in the clamp. By the loosening or

tightening of the wing nut 13 the position of the keeper member 11 is adjusted, as desired. 65

It is to be clearly understood that the provision of the keeper member 11 is to be optional with the user of this device, as it will function effectively without this clamping 70 means.

In Figure 6 a slight modification of the invention has been shown. If it is found desirable to keep the plate and keeper assembled for the sake of convenience this form 75 may be availed of. Instead of providing a slot similar to the open ended slot 12 in the keeper this slot is closed at both ends. A notch 14 on one side of the keeper is designed to maintain the keeper in the position indicated by the dotted lines in Figure 6, by engaging with a lug 15 struck from the plate 7. When the keeper is to be placed in its inoperative position it is swung over so that the notch 14 engages lug 15, in which position 80 it is held until its use is desired.

Having thus described my invention what I claim as new, and desire to secure by Letters Patent of the United States, is:

1. The combination with a door and lock 85 having a keyhole, of an angularly shaped plug, a portion of which is inserted in the keyhole, a plate having a trough fastened to the door, said trough receiving a portion of the plug, and a keeper member for retaining 90 a portion of the plug in the said trough.

2. A plug for keyholes comprising an angularly shaped metal member having a case 95 hardened diamond point, and means functioning through the angular portion of the metal member to retain the point in a keyhole.

3. A device for closing keyholes comprising a plug, a portion of which is adapted to be inserted in a keyhole, means adjustably 100 engaging with the other portion of the plug for retaining it in the hole, a keeper member for positively maintaining the engagement between the plug and the means retaining it in the keyhole. 105

4. A device for closing keyholes comprising a plug, a portion of which is adapted to be inserted in a keyhole, means engaging 110 with the other portion of the plug for retaining it in the hole, a keeper member for positively maintaining the engagement between the plug and the means retaining it in the keyhole, and means for holding the keeper member in adjusted position while inoperative. 115

In testimony whereof I affix my signature.

FREDERICK HEBERLEIN.
